WILLIS F. SIMS AND JACQUE C. MORRELL, OF CHICAGO, ILLINOIS, ASSIGNEES TO UNIVERSAL OIL PRODUCTS COMPANY, OF CHICAGO, ILLINOIS, A CORPORATION OF SOUTH DAKOTA

PROCESS AND APPARATUS FOR CONVERSION OF PETROLEUM OILS

Application filed May 1, 1923, Serial No. 635,822. Renewed November 7, 1928.

This invention relates to improvements in a process and apparatus for the conversion of petroleum oils and refers more particularly to a process relating to the destructive distillation of oils to produce relatively low boiling point oils from higher boiling point oils, the product obtained having the characteristics of gasoline and the like.

The invention has to do also with a particular type of rectifying column or tower evaporator in which are incorporated important novel features.

One of the important objects of the invention resides in the application of heat procured from an internal source which is transferred to the ascending vapors meeting the liquid to be distilled and travelling in a counter-current direction. The particular source of heat is preferably from the distillation of hydrocarbon substances, that is petroleum or any of its distillates, or other hydrocarbons. The vapors may have originated in a cracking still or in an atmospheric pressure still and a subsequent heat transfer effected by condensing the vapors and recycling them to come in radiating contact with the vapors produced by pressure distillation.

The single figure is a diagrammatic side elevational view of the apparatus.

Preferably the invention consists of heating and vaporizing a liquid hydrocarbon and subjecting the vapors to a dephlegmating action, after which they are condensed and collected as liquid distillate. This distillate is then recycled and caused to come in radiating contact or serve as a refluxing medium by cascading the liquid in a manner that the heat given up by the original vapors during the dephlegmation thereof will be utilized to redistill the recirculated condensate. The redistilled fractions are directed to a separate condensing and collecting means and comprise the final product. By utilizing the heat of the system in this manner a most efficient operation may be carried on and a high quality distillate obtained.

Referring to the drawing, the charging stock or oil to be treated is introduced from any convenient extraneous source through

pipe 1 controlled by a valve 2 and is charged by means of a pump 3 through line 4 to a heating coil 5, positioned in a side-fire furnace 6 which is preferably heated by means of gas burners shown diagrammatically at 7. The particular type of apparatus used is of little importance other than that it is necessary to heat the oil as efficiently as possible and restrict the conversion of the oil as far as possible to the vaporizing chamber 8, to which the oil is passed through a line 9 after it has been raised to a conversion temperature in the heating coil 5. A valve 10 is positioned in the transfer line 9 to control the flow of liquid or differential pressures, if such are desired.

The chamber 8 consists of an enlarged receptacle in which the oil is permitted to collect in a substantial body. Upper and lower removable heads furnish means for facilitating the cleaning of the chamber when the carbon collection therein has become objectionable. The vapors evolved in the chamber 8 pass off through the vapor line 11 controlled by valve 12, while the unvaporized products and residual materials may be drawn off either continuously or intermittently through the draw-off lines 13 controlled by valves 14. These residual draw-off lines are positioned at different heights in the chamber in order that the liquid may be drawn off as the carbon collects. The chamber is equipped with try cocks 15 for ascertaining the liquid level of the chamber.

The vapors passing off from the expansion chamber are introduced to a harp-like heat interchanger or dephlegmator 16 positioned in the lower portion 17 of the rectifying column or tower evaporator 18. The vapors from the expansion chamber are introduced into the lower header 16b of the dephlegmator and pass through a plurality of pipes 16a connecting the lower header 16b and the upper header 16c.

During their passage through the refluxing element the vapors are subjected to the cooling action of a liquid which flows over the exterior surface of the reflux condenser separating out the relatively high boiling

point hydrocarbon fractions. This material separated out as liquid condensate is drawn off from the lower header through line 19 controlled by a valve 20 and is directed back to the charging line 4 where it combines with the incoming charging stock and is recycled to the heating stage. The vapors which rise to the upper header 16c pass off through the vapor line 21 in which is interposed a valve 22 and are subjected to a final condensing action in the condenser coil 23 positioned in the condenser box 24. After passing through the condenser coil the vapors are collected as liquid distillate in the receiver 25. The valve 26 is interposed in the line between the condenser coil and the receiver. The receiver is equipped with a liquid level gauge 27, pressure gauge 28, and a pressure relief valve 29.

20 The distillate from the receiver 25 may be returned to the top of the tower evaporator 18 through pipe 30 by manipulation of the valve 31. On being introduced to the rectifying column or tower evaporator the liquid distillate percolates down either over a series of pans which serve to divide the liquid into relatively small particles, or over any desired type of contact material which serves to expose a greater surface of the liquid distillate to the heat given up during dephlegmation of the vapors. This distillate after being cascaded over the contact plates or material in the tower evaporator passes down and circulates around the dephlegmating element 16 which is positioned in the lower portion of the evaporator shown at 17. The heat given off by the dephlegmator 16 is sufficient to re-distill the liquid, the vapors rising through the tower and passing off through the pipe 32 to a condenser coil 33, and thence to the liquid receiver 34 where the redistilled product is obtained, and may be drawn off through the valve 35. A pressure relief valve 37, liquid level gauge 36, and a pressure gauge 38 on the receiver 34 serve to maintain the desired conditions of pressure in the secondary distillation system. This secondary system is preferably operated under atmospheric condition and therefore any excess pressure may be quickly relieved through the relief valve mentioned. The unvaporized liquid which collects in the bottom of the chamber 17 about the dephlegmating element may be drawn off through the pipe 39 and charged by means of a pump 40 back to the line 1 which communicates with the suction side of the pump 3 whereby this liquid distillate is re-run with a charging stock and reflux condensate to the heating stage for re-treatment.

65 Thus the cracked vapors are passed from the expansion chamber into a primary dephlegmator where partial condensation takes place; the reflux liquid passing back to the charging line while the vapors pass

off through a condenser into the receiver 25. This condensed liquid is then forced by pressure of the system into the evaporating tower and cascades over the contact material or obstructing plates partially evaporating from each plate, while any unvaporized material will collect in the bottom of the vapor tower. Evaporation will take place down to the source of heat which is radiated from the primary dephlegmator. Any remaining vapors which are being distilled over from the liquid in the base of the evaporating tower meet the descending stream and furnish heat thereto. The tower may be arranged so that the greater part of distillation or evaporation takes place in the upper portion thereof.

70 It is desirable to insulate the tower in order to have the maximum amount of heat taken up by the descending liquid. This arrangement can be applied either to pressure stills or atmospheric stills. The primary cut can be taken off from the primary dephlegmator and the final cut taken off from the evaporating tower. Other liquid such as crude petroleum may be treated by pumping the crude into the evaporating tower and topping the heavy hydrocarbon for its lighter fractions, the residuum being passed off as charging stock into the cracking process. When operating the secondary distillation 80 as a re-run unit it is preferably operated under atmospheric pressure.

85 By heating mid continent gas oil of approximately 32° Baumé gravity to temperatures ranging from 600° to 900° F., under pressure ranging from 50 to 250 lbs. and re-running the cracked distillate in the manner explained, a good yield of gasoline of new navy specification may be obtained in the final 90 receiver shown at 34.

95 It is desirable that the pressure distillate be treated before redistilling in the evaporating column, and suitable arrangements can be made so that the pressure distillate as it leaves the primary receiver can be brought 100 into contact with, and treated by such reagents as sulphuric acid, water, caustic soda, solutions of litharge in caustic soda and other reagents, in a properly determined order depending upon the type of pressure distillate.

105 Under certain circumstances and in the treatment of certain distillates it may be desirable and a decided advantage to introduce steam or rather inert vapor into the base of the tower evaporator or dephlegmator in order to assist the distillation and obtain a sweet and water white product. For this purpose a steam line 41 controlled by a valve 42 is tapped into the bottom of the tower evaporator, and the steam of the desired character supplied from any convenient source, not shown.

110 We claim as our invention:

115 1. A process for converting oil, consisting 120 in passing the oil through a heating zone 125

whereit is subjected to a conversion temperature, in discharging the heated oil into an enlarged reaction zone wherein substantial vaporization occurs, in passing the vapors from 5 said reaction zone to a dephlegmator, in passing the uncondensed vapors from said dephlegmator to a condenser, and in collecting the resulting distillate, in passing said distillate directly to a zone of heat interchange 10 with the vapors in said dephlegmator whereby the distillate acts as a cooling medium for the vapors in the dephlegmator and the heat of the vapors causes a re-distillation of said distillate, in passing the vapors resulting 15 from such re-distillation of said distillate into intimate contact with additional quantities of said distillate to dephlegmate the last named vapors and to assist in the distillation of said additional quantites of distillate, in passing 20 the uncondensed vapors of the distillate to a final condenser wherein they are condensed, and in collecting this final distillate, in returning reflux condensate withdrawn from said dephlegmator as well as such unvapor- 25 ized distillate as may accumulate in said zone of heat interchange directly to said heating zone while preventing said reflux condensate and unvaporized distillate from contacting with vapors evolved from the oil prior to ad- 30 mission to said heating zone.

2. A process for converting oil, consisting in passing the oil through a heating zone where it is subjected to a conversion temperature, in discharging the heated oil into an enlarged reaction zone wherein substantial vaporization occurs, in passing the vapors from 35 said reaction zone to a dephlegmator, in passing the uncondensed vapors from said dephlegmator to a condenser, and in collecting 40 the resulting distillate, in directing said distillate to a zone of heat interchange with the vapors in said dephlegmator whereby the distillate acts as a cooling medium for the vapors in the dephlegmator and the heat of the 45 vapors causes a re-distillation of said distillate, in passing the vapors resulting from such re-distillation of said distillate into intimate contact with additional quantities of said distillate to dephlegmate the last named 50 vapors and to assist in the distillation of said additional quantities of distillate, in passing the uncondensed vapors of the distillate to a final condenser wherein they are condensed, and in collecting this final distillate, in with- 55 drawing reflux condensate from said dephlegmator, in separately withdrawing such unvaporized distillate as may accumulate in said zone of heat interchange and in returning such withdrawn reflux condensate and un- 60 vaporized distillate directly to said heating zone without permitting any of such reflux condensate and unvaporized distillate to again commingle with vapors evolved from the oil prior to the admission of such reflux 65 condensate and unvaporized distillate to the

heating zone, in continuously withdrawing heavy residual carbon-containing oil from said reaction zone to be isolated from the system, and in maintaining a superatmospheric pressure upon the oil undergoing conversion. 70

3. In an apparatus for converting oil, the combination with means for heating and vaporizing the oil, of a dephlegmating means connected thereto, condensing means connected to the dephlegmating means, means for passing the condensed distillate to a zone of heat interchange with the vapors undergoing dephlegmation in said dephlegmating means to re-distill said distillate, means for passing the vapors evolved from said distillate into intimate contact with additional quantities of the condensed distillate to thereby dephlegmate said vapors and to assist in the distillation of said additional quantities of distillate, 80 means for condensing the vapors resulting from the re-distillation of said distillate, means for collecting the final distillate, means for withdrawing reflux condensate from said dephlegmator separate, means for withdrawing the unvaporized portion of the distillate 85 subjected to re-distillation in said zone of heat interchange, means for returning said withdrawn reflux condensate and unvaporized distillate directly and without contact with vapors to said heating means, and means for maintaining a superatmospheric pressure on the oil undergoing conversion. 90

4. In an apparatus for converting oil, the combination with a heating means, of vaporizing means, means for conveying oil from the heating means to the vaporizing means, dephlegmating means in communication with said vaporizing means, condensing means connected to said dephlegmating means, 100 means for passing condensed distillate to a zone of heat interchange with vapors undergoing reflux condensation in said dephlegmating means, to cause redistillation of said distillate, means for passing the vapors evolved from said distillate into intimate contact with additional quantities of the condensed distillate to thereby dephlegmate said vapors and to assist in the distillation of said additional quantities of distillate, means for 105 condensing vapors resulting from redistillation of said distillate, independent means for withdrawing reflux condensate separated from the vapors in said dephlegmating means and for withdrawing unvaporized portions of the distillate subjected to redistillation in said zone of heat interchange, means for uniting the withdrawn reflux condensate and unvaporized distillate and means for 110 passing the united reflux condensate and unvaporized distillate directly and without contact with vapors to said heating means, and means for maintaining a lower pressure in said zone of heat interchange than is maintained upon the vapors undergoing re- 115 120 125 130

flux condensation in said dephlegmating means.

5. In the cracking of hydrocarbon oils, the improvement which comprises subjecting the oil to cracking conditions of temperature and pressure in a cracking zone, subjecting the evolved cracked vapors to dephlegmation to condense heavier insufficiently cracked fractions, returning the condensed insufficiently 10 cracked fractions to said cracking zone for retreatment in the process, condensing the uncondensed portions of said cracked vapors thereby forming cracked distillate, utilizing portions of said distillate as the cooling medium for said dephlegmation thereby re-distilling said portions of the distillate, passing the vapors evolved by re-distillation of said portions of distillate in intimate contact with additional quantities of said distillate to there- 15 by dephlegmate said vapors and to assist in the redistillation of said additional quantities of distillate, and separately condensing as the final product of the process the remaining uncondensed vapors of said distillate.
